Primary Examiner — Kevin K. Rudzinski*Assistant Examiner* — Jerry Shiuan-Hua Hsu(74) *Attorney, Agent, or Firm* — The Dobrusin Law Firm, P.C.(57) **CLAIM**

The ornamental design for a license plate bracket, as shown and described.

DESCRIPTION

FIG. 1 is a top, front, left side perspective view of a license plate bracket, showing our new design.

FIG. 2 is a top, rear, left side perspective view thereof.

FIG. 3 is a front view thereof.

FIG. 4 is a rear view thereof.

FIG. 5 is a top view thereof.

FIG. 6 is a bottom view thereof.

FIG. 7 is a left-side view thereof; and,

FIG. 8 is a right-side view thereof.

The broken lines are used to show unclaimed portions of the license plate bracket and form no part of the claimed design.
